(57) **CLAIM**

The ornamental design for the golf training apparatus as shown and described.

DESCRIPTION

FIG. 1 shows a front perspective view of the first embodiment of a golf training apparatus;

FIG. 2 shows a rear perspective view of the golf training apparatus of FIG. 1;

FIG. 3 shows a front view of the golf training apparatus of FIG. 1;

FIG. 4 shows a rear view of the golf training apparatus of FIG. 1;

FIG. 5 shows a right view of the golf training apparatus of FIG. 1;

FIG. 6 shows a left view of the golf training apparatus of FIG. 1;

FIG. 7 shows a top view of the golf training apparatus of FIG. 1;

FIG. 8 shows a bottom view of the golf training apparatus of FIG. 1;

FIG. 9 shows a front perspective view of the second embodiment of a golf training apparatus;

FIG. 10 shows a rear perspective view of the golf training apparatus of FIG. 9;

FIG. 11 shows a front view of the golf training apparatus of FIG. 9;

FIG. 12 shows a rear view of the golf training apparatus of FIG. 9;

FIG. 13 shows a right view of the golf training apparatus of FIG. 9;

FIG. 14 shows a left view of the golf training apparatus of FIG. 9;

FIG. 15 shows a top view of the golf training apparatus of FIG. 9; and,

FIG. 16 shows a bottom view of the golf training apparatus of FIG. 9.

1 Claim, 16 Drawing Sheets
